ELEVATING-TRUCK.

1,136,905.

Specification of Letters Patent. Patented Apr. 20, 1915.

Application filed July 31, 1914. Serial No. 854,253.

To all whom it may concern:

Be it known that I, GEORGE E. CLARK, a citizen of the United States of America, and residing at Windsor Locks, in the 5 county of Hartford and State of Connecticut, have invented certain new and useful Improvements in Elevating-Trucks, of which the following is a specification.

This invention relates to elevating trucks 10 of the type which embody a frame and a platform movable vertically and longitudinally with respect to the frame. Such trucks commonly comprise mechanism to move the platform longitudinally on the frame and 15 devices on the latter operable by the longitudinal movement of the platform to lift the same.

This invention is particularly concerned 20 with the mechanism for moving the platform longitudinally relatively to the frame.

An object of the invention is to provide in connection with an elevating truck simple and efficient means operable on the platform to move the latter longitudinally with 25 respect to the frame.

Another object is to provide operating mechanism as described which is operable by the truck handle and attachable or detachable therefrom at will.

30 A further object is to provide mechanism of the class described which is provided with automatic locking devices to hold the platform in its elevated position.

Other objects will appear in the detailed 35 description to follow.

In the accompanying drawings Figure 1 is a side elevational view of my improved 40 operating mechanism as applied to an elevating truck; Fig. 2 is a front elevational view thereof; and Fig. 3 is a view similar to Fig. 1, showing the parts in another position.

In the drawings, only the mechanism for 45 pulling the movable platform longitudinally on the truck frame has been illustrated. The devices for raising the platform, operable by the mechanism specifically shown, has not been illustrated, as that mechanism is known in the art. These devices are, however, fully 50 illustrated and described in the co-pending application of William F. Irrgang, Serial No. 704,352, filed June 18, 1912, to which reference is made.

The frame of the truck is indicated by 55 the numeral 1, to which is attached the rear

wheels and devices for lifting the movable platform 2, as disclosed in the application referred to above. A front wheel 3 is mounted in arms 4 depending from a plate 20 swiveled in the forward portion of the 60 frame 1. Pivoted to the plate 20 is an up-standing forked member 6 and slidably mounted therein is the truck handle 5. Pivotedly attached to the frame at 10 on each side of the forked member 6 are levers 65 9 provided with ears 9'. These levers 9 are mounted adjacent the forked member 6 and the ears 9' are adapted to be engaged by a rod 8 transversely mounted in and fixed to the handle 1. The levers 9 are connected to 70 the movable platform 2 by links 11 which are pivotally connected to the levers 9 at 12, and to the platform 2 at 13.

Formed on the forked member 6 and projecting rearwardly therefrom is a curved 75 member 15. The latter is adapted, when the handle 5 is in the position shown in Fig. 1, to engage the upper surface of the frame 1 and prevent the handle from falling backwardly. Formed on the lower portion 80 of the levers 9 are outwardly extending curved lugs 16. These lugs 16 are adapted, when the levers 9 are in the position shown in Fig. 3, to engage the surface 17 of the frame 1 and limit the movement of the levers 9. A stop member 14, comprising a triangular shaped lug outwardly extending from the frame 1, is adapted to engage the under side of the links 11 when the latter are in the position shown in 90 Fig. 3.

In operation, when it is desired to lift the platform 2 from the frame 1, the handle 5 is moved to the vertical position shown in Fig. 1. As the handle 5 is brought upwardly, the outwardly extending rod 8 attached thereto engages the inclined surface 9² of the ears 9' on the levers 9. Further movement of the handle causes the rod 8 to ride up on the surfaces 9² and finally drop 100 between the ears 9'. The handle 5 may also be pulled outwardly by hand to allow the cross bar 8 to ride over ears 9' and then enter between the ears. A downward movement of the handle 1 then operates to swing 105 the levers 9 on their pivots 10 and to pull the links 11 and the platform 2 forwardly. The movement of the levers 9 is limited by the engagement of the lugs 16 with the surface 17 as described. As the platform 2 110

is moved forwardly, devices on the frame 1 are operated thereby to elevate the platform as fully disclosed in the above-mentioned application.

5 Fig. 3 shows the platform in an elevated position. It is to be noted particularly that, when the platform 2 is elevated, as there shown, the levers 9 and links 11 are arranged to hold the platform and load thereon in elevated position without other elaborate locking devices. The levers 9 and links 11 form a toggle and, when they are in the position shown in Fig. 3, the center line of the link 11 lies below the pivot 10 of the lever 9. As further clockwise rotation of the lever 9 is prevented by the engagement of lug 16 and surface 17, it is impossible for the platform 2 to drop. It is also to be noted that, when the platform 2 and operating mechanism are in an elevated position, the handle 5 may be disengaged to draw the truck and, when so disengaged, is free to swing laterally and turn the swiveled wheel 3. It is also to be noted 25 that the handle may be used independently for steering and drawing the truck whether the platform is up or down.

It is recognized that many modifications of the structure disclosed may be made without departing from the scope of my invention which is more truly defined in the appended claims than in the foregoing specific description.

What I claim is—

35 1. In an elevating truck, the combination of a frame mounted on wheels one of which is swiveled for steering, a platform arranged over the frame and horizontally movable with respect thereto, means to move said platform horizontally, comprising a handle pivotally connected with said swiveled wheel, levers pivotable on said frame and provided with slots, a cross bar on said handle operable by the latter for positioning in said slots to operably connect the handle and levers to swing the latter by the former and link connections pivotally mounted between and on said levers and platform, whereby the latter may be moved 45 horizontally on said frame as said levers are moved by the handle.

2. In combination with an elevating truck having a frame mounted on wheels with a

swiveled wheel at the front, a platform movable on the frame, means to move said platform, comprising, a handle pivoted to said swiveled wheel, levers pivotable to said frame, ears on the ends of said levers, a cross-bar on said handle adapted to engage said ears at will to move said levers, and link connections between said levers and said platform, whereby the latter may be drawn forwardly as said levers are moved, said levers and link connections forming a toggle having a part to engage the frame 65 and adapted to hold the platform in its elevated position when the toggle centers are out of line.

3. In combination with an elevating truck having a frame mounted on wheels and with a swiveled wheel at the front, a platform movable on the frame, a U-shaped member pivoted to said swiveled wheel, a handle slidable in said U-shaped member, levers pivotable to said frame, ears on the ends of said levers, a cross-bar on said handle adapted to engage said ears at will to move said levers, and link connections between said levers and said platform, whereby the latter may be drawn forwardly, as said 70 levers are moved.

4. In combination with an elevating truck having a frame with wheels at the rear and a swiveled wheel at the front, a platform movable on the frame, and devices on the frame to lift the platform as it is drawn forwardly on said frame, a U-shaped member pivoted to said swiveled wheel, a handle slidable in said U-shaped member, levers pivotable to said frame, ears on the 90 ends of said levers, a cross-bar on said handle adapted to engage said ears at will to move said levers, link connections between said levers and said platform whereby the latter may be drawn forwardly, as said 95 levers are moved, and elevated by said devices, said levers and link connections forming a toggle adapted to hold the platform in its elevated position, and stop members on said levers adapted to engage with said frame when the platform is elevated and limit the movement of said levers.

GEORGE E. CLARK.
